Filed Nov. 26, 1965, Ser. No. 88,228

Term of patent 14 years

(Cl. D56—1)

FIG. 1

FIG. 2

FIG. 3

FIG. 4

FIG. 1 is a top plan view of the tambourine embodying my new design;

FIG. 2 is an elevational side view of a fragmentary portion thereof;

FIG. 3 is a bottom plan view thereof; and

FIG. 4 is a side elevational view thereof.

The characteristic feature of my new design resides in the band having a groove which extends continuously about one edge and in which the edge of the skin and hold-down tape are received.

I claim:

The ornamental design for a tambourine, as shown and described.
